UNITED STATES PATENT OFFICE

WILLIAM CRUTCHLOW, OF FULLERTON, PENNSYLVANIA, ASSIGNOR OF ONE-HALF
TO WILLIAM CRUTCHLOW, JR., OF FULLERTON, PENNSYLVANIA

WEFT STOP MOTION MECHANISM

Application filed September 23, 1930. Serial No. 483,836.

This invention relates to looms and particularly to weft-detective means therefor. The object of the invention is to cause the detecting action to occur when the lay or batten is moving backward or from the cloth and yet have the detecting mechanism simple in construction and reliable and efficient in operation. The invention is especially applicable to so-called box-looms, 10 or looms containing several shuttles each called into operation at a time, because in such looms the operations of picking a shuttle and shifting the shuttle-boxes so as to change from one shuttle to another to fully 15 occupy the time when the lay or batten is moving forward that it is practically impossible to provide a detecting means which can act on the forward stroke and yet be simple in construction and reliable and efficient in operation, for it is obvious that the 20 detector means cannot act to detect while the box-shifting is occurring else there would be interference between it and the shifting boxes.

25 In the drawings,

Fig. 1 shows in front elevation the shuttle-box including portion of the lay structure of a loom and embodying the invention;

Fig. 2 is a plan of the shuttle, with the 30 terminals of the detector;

Fig. 3 is a front-elevation, partly in section, of the improved detector means and a part of the loom frame;

Fig. 4 is a section on line 4—4, Fig. 3; and

Fig. 5 shows the detector partly in plan and partly in section, together with a diagram of the electric circuit.

1 designates a side of the loom frame, 2 one of the lay swords, 3 the lay, 4 the frame or stand forming an extension of the lay and in which the shuttle boxes 5 are adapted to be shifted by the box-rod 6 by any well-known means, and 7 the binders for the shuttles, one of which is shown at 9, Fig. 2. All this is 40 substantially according to well known construction. Each binder has an aperture 7a to admit the detector (to be described) into contact, in this example, with the actual filling or weft windings α on the quill 8 of the 45 corresponding shuttle 9 and, if they are ab-

sent or effectively so, into contact with a circuit-closer in the form of a metal tube or band 10 on such quill which is covered by such windings when the quill is full, since in the present example the result of detection of 55 filling-failure is to be transmitted electrically.

A bracket 11 which projects forward from and is affixed to what I term the lay-including structure (2—3—4) has an upstanding tubular pillar 12 formed at the top with a notch 13 and forming a bearing for a vertical spindle 14 which has a collar 15 affixed thereto and provided with a depending pin 16 received by notch 13 and thus limiting the rotary motion of the spindle in each direction. 60 The pillar is surrounded by a spring 17 one end of which is affixed to collar 15, as by screw 15a, and the other to a collar 19 (by being entered into a hole 19a thereof) which is adjustable around the pillar, being held 70 when adjusted by a set-screw 19b, thus to vary the tension of the spring.

On the upper end of the spindle is a collar 20, rotatively adjustable thereon and held 75 where adjusted by a set-screw 20a, and this has affixed thereto an elastic and hence flexible arm or blade 21 which at its free end carries the terminals of the electric circuit. For this purpose I prefer to rebend the end of this arm, as at 21a and also affix to one face 80 of the arm a pad or block 22 so as to afford proper support for the insulating bushing 23 for one of the mentioned terminals, 24, and properly guide the other terminal 25. The mentioned circuit is shown at 26, 27 being its 85 energy source and 28 diagrammatically indicating electro-magnetic means to be actuated, as a solenoid, for, say, causing the stopping of the loom, or any other operation which is to be the incident of detecting failure of filling, the mechanism for which is not shown because it is not here material. The terminals are normally held by springs 29, interposed between their heads and the pad 22, with adjusting nuts 30 thereon abutting arm 90 21, but may yield in the direction to compress the springs. The arm is so positioned that its terminals are opposed to the aperture 7a of that box which happens to be alined with the top of the lay, and due to spring 17 it is 95 100

normally retracted; its movement to enter the terminals through said aperture and one, 9a, in the shuttle and against the windings is effected as follows:

5 On the lower end of spindle 14 is adjustably fixed, by means of a set-screw 31a, an arm 31 having a roller 31b. On the frame 1 is fixed a bracket 32 having a slot 32a in which is adjustable toward the spindle a stud 33
 10 clamped to the bracket by a nut 34. On this stud is pivoted a member 35 held against a stop 36 (or rearward of the loom) by a spring 37 and which, because it has a camming action on the detector or feeler formed by spindle 14 and its two arms, I term a cam. This cam projects in the path of the roller 31b arm 31. When the lay moves forward the cam yields and allows it to pass, at once returning against the stop; when the lay moves back-
 15 20ward the cam, then engaging the stop, cams the detector in the direction to enter the terminals 24—25 at the apertures 7a—9a then alined with the lay to "feel" for the windings in the shuttle there present, the detector yielding as it wipes past the cam due to the flexibility of its arm 21.

Thus, when the lay is moving forward the shifting of the boxes may take place, the detector being then held retracted clear of the 30 boxes by spring 17 and the cam being wiped aside or in effect then idle. When the lay moves back the cam, now against its stop and active, shifts the detector toward the boxes (now at stand-still) and enters its terminals 35 against the windings in the zone of the band 10, the detector immediately retracting under tension of spring 17 when during this movement of the lay it passes the detent as described. Of course, if on any such movement of the detector to "feel" for the windings the latter are substantially absent, so that the band 10 will close the circuit, the means 28 will be energized to cause stopping of or other operation in the loom.

45 Having thus fully described my invention what I claim is:

1. In a loom, the combination of a loom frame, a backward-and-forward-moving lay structure having a shuttle box, a shuttle movable into and out of the box and having a circuit-closer, an open circuit containing electro-magnetic means to be actuated, a member carrying the circuit terminals and movable on said structure in opposite directions and 50 when moved in one direction adapted to cause contact of the terminals with the circuit-closer, and means to move said member first in the direction to cause such contact during each backward movement of said structure 55 and then in the opposite direction, said means including a cam past which said member moves with said structure and arranged to move said member in one of said directions.

2. In a loom, the combination of a loom frame, a backward-and-forward-moving lay 60

structure having a shuttle box, a shuttle movable into and out of the box and having a circuit-closer, an open circuit containing electro-magnetic means to be actuated, a member carrying the circuit terminals and movable to either of two positions in one of which the terminals contact with the circuit-closer and in the other of which they are retracted therefrom, said member being normally held in the second position, and cam means, past 70 which said structure moves, to move said member to the first position during each backward movement of said structure.

3. In a loom, the combination of a loom frame, a backward-and-forward-moving lay 80 having a shuttle box, a shuttle movable into and out of the box and having a circuit-closer, an open circuit containing electro-magnetic means to be actuated, a member carrying the circuit terminals and movable to either of two positions in one of which the terminals contact with the circuit-closer and in the other of which they are retracted therefrom, said member being normally held in the second 85 position, and a cam on the frame arranged to cam said member to the first position and then release the same during each backward movement of the lay, said member and cam being yieldable one to the other on each forward movement of the lay.

4. In a loom, the combination of a loom frame, a backward-and-forward-moving lay having a shuttle box, a shuttle movable into and out of the box and having a circuit-closer, an open circuit containing electro-magnetic 100 means to be actuated, a member carrying the circuit terminals and movable to either of two positions in one of which the terminals contact with the circuit-closer and in the other of which they are retracted therefrom, said member being normally held in the second position, and a cam on the frame arranged to cam said member to the first position and then release the same during each backward movement of the lay, said member and cam being yieldable one to the other on each forward movement of the lay, and said member being in itself yieldable and adapted to yield to the cam when it passes the same on rearward movement of the lay.

5. In a loom, the combination of a loom frame, a backward-and-forward-moving lay having a shuttle box, a shuttle in the box, a feeler movable to either of two positions in one of which it feels the shuttle in the box and in the other of which it is retracted therefrom, and means to move the feeler first in one direction into feeling relation to the shuttle during each backward movement of the lay and then in the opposite direction, said means including a cam past which said feeler moves with the lay and arranged to move the feeler in one of said directions.

6. In a loom, the combination of a loom frame, a backward-and-forward-moving lay 120

having a shuttle box, a shuttle in the box, a
feeler movable to either of two positions in
one of which it feels the shuttle in the box and
in the other of which it is retracted there-
5 from, said feeler being normally held in the
retracted position, and a cam on the frame
arranged to cam said feeler to the first posi-
tion and then release the same during each
backward movement of the lay, said feeler
10 and cam being yieldable one to the other on
each forward movement of the lay.

7. In a loom, the combination of a loom
frame, a backward-and-forward-moving lay
15 having a shuttle box, a shuttle in the box, a
feeler movable to either of two positions in
one of which it feels the shuttle in the box and
in the other of which it is retracted there-
from, said feeler being normally held in the
retracted position, and a cam on the frame
20 arranged to cam said member to the first posi-
tion and then release the same during each
backward movement of the lay, said member
and cam being yieldable one to the other on
each forward movement of the lay and said
25 member being in itself yieldable and adapt-
ed to yield to the cam when it passes the same
on rearward movement of the lay.

In testimony whereof I affix my signature.
WILLIAM CRUTCHLOW.
